UNITED STATES PATENT OFFICE

2,166,803

MOMENTARY CONTACT PUSH SWITCH

Frank C. De Reamer, Bridgeport, Conn., assignor
to General Electric Company, a corporation of
New York

Application July 29, 1936, Serial No. 93,237

2 Claims. (Cl. 200—159)

The present invention relates to push button operated electric switches.

The object of my invention is to provide an improved construction and arrangement in switches of this type, and, for a consideration of what I believe to be novel and my invention, attention is directed to the accompanying description and the claims appended thereto.

In the accompanying drawing, Fig. 1 is a side elevation of an electric switch embodying my invention; Fig. 2 is a sectional elevation taken on line 2—2 of Fig. 1; Fig. 3 is an exploded view of the switch; Fig. 4 is a bottom plan view of the switch; Fig. 5 is a sectional elevation of a modification; and Fig. 6 is an enlarged view showing the manner of assembling the terminal.

Referring to the drawing, I have shown my invention applied to a switch having a housing 1 of molded insulating material having bosses 2 at opposite sides thereof. In the upper faces of the bosses are recesses 3 for receiving terminals 4 which comprise V-shaped metal strips with the sides 5 of the V pressed tightly together. At the junction of the sides of the V the terminals are provided with openings through which extend the bared ends 6 of stranded line conductors 7. With this arrangement the bared ends of the conductors are fanned out and forced into firm electrical contact with the sides 5 of the terminals when the sides of the terminals are clamped together. From another aspect, the terminals 4 can be considered as a strip having one end 5 folded over the other, there being an opening in the strip intermediate its ends through which the bared end of a conductor is inserted and held in place by pressing the ends of the strip together. The terminals are held in the recesses 3 by projections 8 on the terminals which fit into depressions 9 in the recesses. The upper end of the housing is closed by a sheet or member 10 of insulating material which is provided with ears 11 extending over the bosses 2. When the member 10 is secured to the top of the housing, the ears 11 clamp the terminals securely in the recesses 3 and also increase the clamping effect of the sides of the terminals on the bared ends of the conductors thereby providing a connection between the terminals and the conductors which does not require soldering.

The member 10 is secured to the top of the housing by a metal plate 12 having tangs 13 which are bent over a bead 14 at the top of the housing. As shown in Figs. 1 and 4, tangs 13 engage the sides of the bosses 2 and locate the metal plate 12 on top of the housing. The tangs 13 also ex-

tend on either side of the ears 11 and thereby prevent turning of the member 10 with respect to the housing. The conductors 7 are supported by an arm 12a on the plate 12. The conductors are first drawn tightly against the switch housing 5 and are secured to the arm 12a by ears 12b which are folded over the conductors. The metal plate 12 is secured to the lower end of a threaded sleeve 15 by spun-over portions 16. The switch may be mounted by extending the sleeve through 10 a support and by clamping the support between nuts 17 threaded on the sleeve.

In the sleeve 15 is a push button which comprises a drawn tubular metal shell 18, the closed end of the shell projecting beyond the sleeve 15 15 where it may be engaged by the operator, and the tubular body portion of the shell being slidable in the sleeve. Within the shell 18 is an operating rod or spindle 19 which is secured therein by a washer 20 wedged into the shell. The operating rod has a head 21 which provides a shoulder 22 co-operating with the washer to hold the operating rod in place. The lower end of the operating rod is guided in an opening 23 in the member 10. There is sufficient clearance between the washer and the operating rod, and between the head 21 of the operating rod and the end of the shell 18, so that the operating rod may have a limited angular movement in the shell, or, viewed from another aspect, the operating rod 20 is free to swivel in the push button. The swiveling of the operating rod prevents binding of the operating rod in the guiding opening 23 in case the member 10 is assembled so that this opening is not in exact alignment with the operating rod. 25 The operating rod 19 projects below the member 10 and the projecting end is provided with a reduced portion 24 on which is loosely carried a washer 25 of insulating material. The washer 25 is held in place by turning over the end of the operating rod to form a flange so that the washer fits loosely between the flange and the shoulder at the upper end of the reduced portion 24. Around the periphery of the washer is a metal rim 26 which serves as a bridging contact which 45 co-operates with the inner ends of terminals 4 to complete an electric circuit between the terminals.

The push button is biased to the outer position shown in Fig. 2 by a coil spring 27 which is arranged around the operating rod and between the member 10 and the washer 20. The spring biases the push button outwardly so that the metal rim 26 is normally held against the terminals 4 to complete a circuit between the ter- 50 55

minals. There is sufficient clearance between the washer 28 and the groove 24 so that the metal rim 26 can align itself with the terminals and thereby provide uniform contact with the terminals. The circuit between the terminals is broken by pushing the push button inward.

5 The switch shown in Figs. 1 to 4 inclusive is of the type in which the circuit through the switch is normally closed. In Fig. 5 is shown a modification of the switch in which the circuit through the switch is normally open.

10 The construction of the switch shown in Fig. 5 is identical with the switch shown in Figs. 1 to 4 inclusive except for the construction of the terminals, the stationary contacts, and the push button and the identical parts are indicated by the same reference numerals. The terminals comprise angular metal strips 30, the upper ends of which fit within the depressions 8, and the lower ends of which serve as solder lugs which are soldered to the bared ends 6 of the line conductors 7. The upper ends of the strips 30 are secured to contacts 31 which fit in grooves 32 in the switch housing. At the bottom the contacts are provided with a stepped portion 33 which is arranged to co-operate with the contact 26 on the lower end of the operating rod 18. Between the head 21 of the operating rod and the end of the shell 18 is a coil spring 34. This spring normally holds 15 the shoulder 22 of the operating rod against the washer 28, but permits the operating rod to move upwardly in the push button when the resistance offered to further movement of the operating rod exceeds the tension of the spring. The push button is normally held in the position illustrated by the coil spring 27 which is arranged between the member 18 and the washer 28. In this position the contact 26 is held against the underside of the member 18 and the circuit between the

15 contacts 31 is open. When the push button is pushed inward the contact 26 is moved into engagement with the stepped portions 33 of the contacts 31, thereby completing the circuit between the contacts. During the initial movement of the push button the spring 34 is not compressed and the operating rod occupies the position in the push button illustrated. As soon as the contact pressure between the contacts 26 and 33 exceeds the tension of the spring 34 the operating rod moves upwardly with respect to the push button. The spring 34, therefore, provides a cushion between the operating rod and the push button, which limits the contact pressure between the contacts 26 and 33.

18 What I claim as new and desire to secure by Letters Patent of the United States is:

1. In an electric switch, a housing of insulating material, a sleeve secured to said housing, a member of insulating material clamped between said sleeve and said housing, recesses in said housing adjacent said member, terminals clamped in said recess by said member, and a spindle guided in said sleeve and said member of insulating material carrying contacts cooperating with 25 said terminals.

2. In an electric switch, a housing of insulating material, a sleeve secured to said housing, a member of insulating material clamped between said sleeve and said housing, recesses in said housing adjacent said member, terminals clamped in said recess and projecting within the housing, the upper sides thereof being in contact with the under side of said member, and a spindle guided in said sleeve carrying contacts below said terminals movable upward into engagement with the under sides of the terminals.

FRANK C. DE REAMER.
